UNITED STATES PATENT OFFICE

AINSLIE T. CARTER, OF COLDWATER, NEW YORK, ASSIGNOR TO GENERAL RAILWAY SIGNAL COMPANY, OF ROCHESTER, NEW YORK

ELECTROPNEUMATIC VALVE

Application filed May 10, 1929. Serial No. 361,980.

This invention relates to automatic train control systems, and more particularly to electro-pneumatic valves for controlling, pneumatically operated movable ramps, 5 pneumatically operated brake valve actuators, or other pneumatically operated means for controlling the movements of trains.

In the construction of automatic train control systems, it is desirable to have such a 10 system organized to operate upon the "closed circuit" principle. One such system of the "train stop" type, has a movable ramp so arranged, that, if its control means, which is inter-connected with the signal system, assumes a stop position or becomes severed, the 15 ramp moves to a predetermined position under the force of gravity, in which position, the ramp trips an electric switch or other valve controlling lever on a moving train to effect an automatic brake application. Under non-stopping conditions, the ramp is 20 moved by the application of air pressure to a controlling piston, out of the range of contact with the tripping device on the moving train. In such a case, where the controlling 25 electro-pneumatic valve is operated by alternating current, it is desirable to have the electro-pneumatic control valve immune to stray direct current potentials, which might 30 produce a false condition.

Also, as the system provides, that the controlling electro-pneumatic valve shall be normally energized, it is desirable, that the device shall consume a minimum amount of 35 power when in the energized position.

With the above and other considerations in mind, it is proposed to provide an alternating current electro-pneumatic valve, which is responsive to alternating current only and 40 which will require a minimum value power when in fully energized position.

Other objects, purposes and characteristic features will in part be obvious from the accompanying drawings and in part pointed 45 out, as the description of the invention pro-

gresses. In describing the invention in detail, reference will be made to the accompanying drawings, in which:—

Fig. 1 shows, in a wholly diagrammatic manner, a portion of an automatic train stop system in which the electro-pneumatic valve 50 of the present invention is incorporated;

Fig. 2, is a side elevation of the electro-pneumatic valve as included within the present invention, showing the valve chambers 55 and coil in cross section;

Fig. 3 is an end view of the electro-pneumatic valve as shown in Fig. 2;

Fig. 4 is a cross section view of the armature shown in Fig. 1.

Although in practice, a train control system, may govern the passage of traffic over a railroad in accordance with the indication of wayside signals at passing siding, intermediate signals, and signals at cross-overs and the like, the present invention has for convenience been shown as applied to the apparatus located at the permissive-block-signal SE, which governs the passage of traffic in an east bound direction over a track section 60 TK. This track section has the usual track battery located at the east end (not shown) and the usual track relay TR at the west end, which governs the energization or de-energization of the electro-pneumatic valve EPV 65 through a front contact FC of the relay TR from the line transformer T. The preceding track section TK° has its similar control apparatus of which the track battery TB° 70 and track relay TR° only are shown.

The valve EPV in turn governs the application or non-application of air pressure to the cylinder RC, which either forces a lever L associated with a piston PT, to rotate in a clock-wise direction or permits a weight W to 75 force lever L in a counter-clock-wise direction, in respect to the pivot point P, moving ramp R which is attached to the right hand end of lever L, out of, or into, an engaging position respectively. Thus, an arrangement is 80 85 90 95

so organized, that, when a train enters the track section TK, the relay TR is de-energized, the EPV valve is deenergized, the air pressure forcing the piston PT upward, is removed and vented to atmospheric pressure, all of which permits the weight W to force the movable ramp R upward into such a position, that it will engage a switch or other tripping means on any passing train to effect an automatic brake application, so long as track section TK is occupied.

There is shown in Fig. 2 a side view of the electro-pneumatic valve as included within the present invention, having an armature A, placed within a suitable recess in a stator S, being a combination so arranged as to furnish control means for a valve combination V.

The stator S is made of soft iron laminations 1, so shaped that, when said laminations are held together by bolts 2 and nuts 3, an inverted U-shaped stator is formed having a recess, in which the armature A may be mounted. With the coil 4 placed upon the cross piece S¹ of the stator S, and the stop 5 fastened to the stator by a bolt 2, the complete stator S is mounted upon the frame 6.

The armature A is composed of soft iron laminations 7, that are stamped into a circular shape, being formed with flat portions on two opposite sides, to allow a continuous copper band 8 to fit within the circular outline of the armature. The lamination stampings 7 also, have centrally located holes, to receive an axle 9. These lamineæ 7 and copper band 8 are held together by the bushings 10 and 11 riveted together at 12 and 13. The axle 9 passes through the armature A and a lever 14, and are fastened together by rivets 15 and 16. This axle 9 has bearings 17 and 18, which turn on bearing set screws 19 and 20, with the set screws mounted in frames 21 and 6, and locked with usual lock-nuts. The armature A is mounted within the recess in the stator S in such a manner that the center line of the axle 9 is slightly lower than the center line of the recess in the stator. This makes the air gaps 6^a and 6^b slightly less than the air gaps 6^c and 6^d, for reasons hereinafter explained.

The valve V consists of three circular chambers which have suitable passages for external connections. The lower chamber SC is a supply chamber connected permanently to a suitable supply of air pressure through an external passage. This chamber SC is connected to the control chamber CC through the port 22, and is connected to the exhaust chamber EC, through port 23. The central control chamber CC is connected through an external passage to control cylinder RC and piston PT, while the exhaust chamber is opened to the atmosphere through a suitable external passage. The ports 22 and 23 are controlled by suitable valve plungers 24 and 25 respectively, which are

mounted upon the valve stem 26, and biased to an upper extreme position, by the coil spring 27. However, the valve stem 26 is normally held in a lower extreme position with coil spring 27 compressed by a foot 28^a of a lever 28, which is pivotally suspended upon bearing set screws 29 and 30 mounted upon the frames 6 and 21. This lever 28 is connected to the armature A through the toggle lever 31 and the lever 14, transmitting the motion of the armature A to the valve stem 26.

It can be readily understood, that if the armature A is rotated in a clock-wise direction, until the lever 28 comes into contact with stop 5, the foot 28^a will move upward allowing the valve stem 26 to be forced upward by the coil spring 27, thus closing the outlet port 22 of the supply chamber SC, and opening the outlet port 23 venting the control chamber CC to atmosphere through the exhaust chamber EC. But, with the armature in its energized position as shown in Fig. 1, the valve stem 26 is forced down, compressing the coil spring 27 and closing the port 23 and opening the port 22.

It will be noted, that the stop 5 is mounted upon the stator S in such a position, that it allows the armature to rotate in a clock-wise direction to a predetermined point.

Assuming the coil 4 to be energized with alternating current of a suitable potential, flux passes through the magnetic circuit including the stator laminations 1 and the armature laminations 7. As the air gaps 6^a and 6^b, included in this magnetic circuit, are of a lesser value than the air gaps 6^c and 6^d, a greater amount of magnetic pull will be applied below than above the center line of the armature A. This gives a desirable result in that, the greater magnetic pull is in a common direction with the force of gravity, eliminating the natural vibration of a non-rotating magnetic body within a field of alternating flux.

With the coil 4 energized and the copper band 8 on armature A in a vertical or 90 degree position, there is no torque produced on the armature A, although there is a current flowing in the copper band 8, due to the fact that the direction of the flux produced by the induced current is opposite and parallel to the direction of the primary flux. Also, there is no torque on the armature A, when it is in a horizontal or 180 degree position, because there is no current induced in the copper band 8. Thus, the torque produced on the armature A varies from zero at the 90 degree position, to a maximum value at approximately the 135 degree position, and back to zero at the 180 degree position.

The mechanical advantage obtained by the levers 14, 28 and 31 in a toggle combination, varies from unity at such time that the lever 14 is perpendicular to the direction of the force applied to the lever 28, to an approach to infinity as the direction of the

force applied to lever 28 coincides with the center line of armature A.

A combination can thus be obtained by combining the characteristics of the above 5 described armature and toggle arrangement, to obtain a maximum out-put of force on the lever 28 over a limited movement of rotation. In the electro-pneumatic valve of the present invention, this maximum value is obtained by varying the angle between the copper band 8 and the lever 14.

It is also readily understood, that with a fully energized position chosen such that the copper band 8 is approaching the 180 15 degree position, the current flowing in the copper band 8 is approaching zero. Hence, the total power required to operate the electro-pneumatic valve EPV is at a minimum value when in the energized position.

The above rather specific description of one form of this invention, is given solely for the sake of illustration, and is not intended in any manner whatsoever, in a limiting sense, as obviously, the invention can be embodied in 20 many different physical forms, and is susceptible of numerous modifications, and all such forms and modifications are intended to be included in this invention as come within the scope of the appended claims.

Having described my invention, I now claim:

1. Trackway apparatus for train control systems of the mechanical trip train stop type comprising, an electro-responsive device, which, when energized, places a mechanical trip in its inactive position, and including a stator having a stator winding associated therewith, and a rotor having a short circuited winding lying in one plane on said 35 rotor, whereby, if alternating current is applied to said stator winding, said rotor will turn through an angle to hold said mechanical trip in its inactive position by magnetic repulsion of said short circuited winding, said device being non-responsive to the flow of direct current in said stator winding.

2. Trackway apparatus for train control systems of the mechanical trip train stop type comprising, an electro-responsive device, 50 which, when energized, places a mechanical trip in its inactive position, and including a stator having a stator winding associated therewith, a circular rotor having a short circuited winding lying in one plane on said 55 rotor, said circular rotor being mounted to turn through a predetermined angle within a circular recess in said stator, whereby, if alternating current is applied to said stator winding, said rotor will turn through an angle to hold said mechanical trip in its inactive position by magnetic repulsion of said short circuited winding and said mechanical trip cannot be held in its inactive position by the flow of direct current in said stator winding, said circular rotor having its axis of ro-

tation positioned below the center line of said circular recess in said stator to thereby minimize vibration during energization.

3. Apparatus for train control systems of the mechanical trip train stop type comprising, 70 an electro-responsive device including a stator having a stator winding associated therewith, a circular rotor having a low resistance short circuited winding lying in one plane on said rotor, said circular rotor being mounted to turn through a predetermined angle within a circular recess in said stator, the axis of rotation of said rotor being positioned below the center line of said circular recess in said stator, operating means to hold a mechanical trip in its inactive position, and to allow said mechanical trip to assume its active position, inter-connecting means to transmit motion of said rotor to said operating means including, a controlled lever, a power lever connected to said rotor, and a connecting lever so connecting said power lever to said controlled lever that said controlled lever receives a maximum value of energy due to a predetermined angle between the 80 plane of said short circuited winding and the lever arm of said power lever so that said rotor turns to an energized position in response to the application of alternating current to said stator winding to hold said mechanical trip in one position.

4. In an electro-pneumatic valve for automatic train control on railroads, an electro-responsive means comprising, a stator having a stator winding, a rotor having a short circuited winding lying in one plane on said 100 rotor, said rotor being mounted pivotally to rotate through a limited angle in such a position as to complete the magnetic circuit of said stator, a valve controlled by said electro-responsive means, through lever means comprising, a controlled lever, a driving lever, and a toggle lever connecting said controlled lever and said driving lever, whereby, if alternating current be applied to said stator winding, said rotor turns through an 105 angle to control said valve from one biased extreme position to another extreme position, said electro-responsive device being non-responsive to the flow of direct current in said stator winding.

5. In a controlling device for automatic train control systems, an electro-responsive means comprising, a stator having a stator winding, a rotor having a short circuited low 110 resistance metal band lying in one plane thereon, said rotor being mounted to rotate through an angle within the magnetic flux path of said stator, a controlling device associated with said electro-responsive means such that said controlling device acts in accordance with the energization and de-energization of said electro-responsive means through lever means comprising, a controlled lever, a driving lever, and a toggle lever so 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 connecting said controlled lever and said driving lever that said controlled lever receives a maximum value of energy due to a predetermined angle between the place of said short circuited low resistance metal band on said rotor and said driving lever attached to said rotor, through said angle of rotation, said rotor being in response to the application of alternating current but not to the application of direct current.

6. In a controlling device for train control systems, an electro-responsive means comprising, a laminated stator having a primary coil; a laminated circular armature having a short-circuited secondary coil, said circular armature being mounted to turn through a predetermined angle within a circular recess in said stator, said circular armature having its axis of rotation below the center line of said circular recess in said stator, a controlling means associated with said electro-responsive means in such a manner, that said controlling means acts in accordance with the energization or de-energization of said electro-responsive means through a lever arrangement comprising, a controlled lever, a power lever, and a link lever connecting said controlled lever with said power lever, whereby said controlled lever receives a maximum value of energy due to a certain angle between the plane of said short circuited secondary coil and the lever arm of said power lever attached to said armature, and whereby said armature turns to an energized position in response to the application of alternating current to said primary coil, but will not respond to the application of direct current to said primary coil.

7. In a control device for use in systems for the automatic governing of train movements on railroads, an electro-responsive means comprising, a soft iron laminated stator having a primary coil, a soft iron laminated circular armature having a short circuited secondary coil, said circular armature being supported to turn through a certain angle within a circular recess in said stator, said circular armature having its axis of rotation positioned below the center line of said circular recess in said stator, whereby, the flow of alternating current in said primary coil cannot cause excessive mechanical oscillation of said armature, a controlling means associated with said electro-responsive means so that said controlling means acts in accordance with the energization and de-energization of said electro-responsive means through a lever arrangement comprising, a controlled lever, a driving lever connected to said armature, and a toggle lever connecting said controlled lever with said driving lever whereby said controlled lever is moved from a biased position to an opposite extreme position in response to the application of al-

ternating current to said primary coil, said electro-responsive means being immune to operation by D. C.

8. Apparatus for train control systems of the mechanical trip train stop type comprising, an electro-responsive device including a stator having a stator winding associated therewith, a circular rotor having a low resistance short circuited winding lying in one plane on said rotor, said circular rotor being mounted to turn through a predetermined angle within a circular recess in said stator, the axis of rotation of said rotor being positioned below the center line of said circular recess in said stator.

9. Apparatus for train control systems of the mechanical trip train stop type comprising, an electro-responsive device including a stator having a stator winding associated therewith, a circular rotor having a low resistance short circuited winding lying in one plane on said rotor, said circular rotor being mounted to turn through a predetermined angle within a circular recess in said stator, the axis of rotation of said rotor being positioned below the center line of said circular recess in said stator, operating means to hold a mechanical trip in its inactive position, and to allow said mechanical trip to assume its active position, inter-connecting means to transmit motion of said rotor to said operating means including, a controlled lever, a power lever connected to said rotor, and a connecting lever so connecting said power lever to said controlled lever that said controlled lever receives a maximum value of energy due to a predetermined angle between the plane of said short circuited winding and the lever arm of said power lever so that said rotor turns to an energized position in response to the application of alternating current to said stator winding to hold said mechanical trip in one position, said electro-responsive device being immune to operation by direct current.

10. In a controlling device for train control systems, an electro-responsive means comprising, a laminated stator having a primary coil, a laminated circular armature having a short-circuited secondary coil, said circular armature being mounted to turn through a predetermined angle within a circular recess in said stator, and train control means operated by said electro-responsive means.

11. For use in train control systems, in combination, a translating device having a stator with a primary coil and an armature with a short-circuited secondary coil lying in one plane on the rotor, a control means operated by said device, and operating means connecting the device to the control means, comprising, a controlled lever, a power lever, and a link lever connecting said controlled lever with said power lever, whereby said controlled lever receives a maximum value of

energy due to a certain angle between the plane of said short-circuited secondary coil and the lever arm of said power lever attached to said armature, and whereby said 5 armature turns to an energized position in response to the application of alternating current to said primary coil, but will not respond to the application of direct current to said primary coil.

10 In testimony whereof I affix my signature.
AINSLIE T. CARTER.
